UNITED STATES PATENT OFFICE.

JAMES ROBERTSON, OF LASSWADE, GREAT BRITAIN, ASSIGNOR, BY MESNE ASSIGNMENTS, TO L. ASHMUN & CO., OF PATERSON, NEW JERSEY.

IMPROVEMENT IN APPARATUS FOR REPAIRING KNOTTER, STRAINER, OR SCREEN PLATES OF PAPER-MACHINES.

Specification forming part of Letters Patent No. 140,166, dated June 24, 1873; application filed November 9, 1872.

To all whom it may concern:

Be it known that I, JAMES ROBERTSON, of Lasswade, in the county of Mid Lothian, Scotland, have invented a new and useful Improvement in Apparatus for Repairing Knotter, Strainer, or Screen Plates of Paper-Machines, of which the following is a specification:

Figure 1 represents a strainer-plate secured to the block, or bed. Fig. 2 is a detail longitudinal section taken through the line *x x*, Fig. 1. Fig. 3 is a detail cross-section taken through the line *y y*, Fig. 1. Fig. 4 is a detail cross-section enlarged and showing the tool in place. Fig. 5 is a side view of the tool.

Similar letters of reference indicate corresponding parts.

My invention has for its object to furnish an improved apparatus for repairing strainer-plates, the slots of which have been widened by the wear and the corrosion due to the straining action and the acids in the pulp, so as to enable the said plates to be again used; and it consists in the mode of lessening or reducing the slots in a strainer-plate, in the tool constructed as hereinafter shown and described, to adapt it for use in reducing the slots in a strainer-plate, as hereinafter set forth.

A represents the strainer-plate, about the construction of which there is nothing new. *B* is the table, block, or bed, upon which the plate *A* is laid, to be operated upon. The bed *B* is made of iron, sufficiently heavy to support the plate *A* firmly, and which may be strengthened with ribs or flanges, either or both, upon its lower side. The bed *B* may be provided with legs of such a length as to raise the bed to a convenient height. *C* are clamps extending across the plate *A*, and the ends of which are bent downward and inward to overlap the lower side of the bed *B*, as shown in Fig. 3. In the clamps *C* are formed screw-holes, in which are inserted the screws *D*, the forward ends of which rest against bars *E*, laid upon the plate *A* beneath the clamps *C*, as shown in Figs. 2 and 3, so that by turning the screws *D* forward the plate *A* will be pressed down firmly upon the bed *B*. The plate *A* is further secured to the bed *B* by the edge-clamps *F*, which cross the edges of the plate *A* and bed *B*,

and the ends of which overlap the upper side of the plate *A* and the lower side of the bed *B*, as shown in Figs. 1, 2, and 3, where they are secured in place by wedge-keys *G*, as shown in Fig. 2. *H* is the body or shank of the tool, the lower end of which is slotted to receive the blade *I*, which is secured in place by screws, bolts, or other convenient means. The blade *I* must be of a thickness exactly equal to the required width of the slots in the plate *A*. The lower end of the shank or handle *H* is so formed as to press or draw the metal of the plate *A*, at the edges of the slots in said plate, inward against the sides of the blade *I*, thus reducing the size of said slots.

In using the apparatus the plate *A* is secured to the bed or block *B*, in the manner hereinbefore described. The blade *I* is then inserted in the slots of the plate *A*, and by a few blows of a hammer upon the upper end of the handle *H* the metal of the plate *A* will be drawn or packed against the blade *I*, reducing the slot again to the required size, the blade *I* acting as a gage.

The plate *A*, when repaired in this way, is even better, and will last longer, than when new, as the metal is compressed along the slots and is thus better adapted to resist the wear and the action of the acids.

One or both the side edges of the blade *I* may project in hook form, as shown in Fig. 5, so that it may be used for clearing the slots before reducing their width.

Having thus described my invention, I claim as new and desire to secure by Letters Patent—

1. The mode of lessening or reducing the slots in a strainer-plate, substantially as herein shown and described, and for the purpose set forth.
2. The tool *H I*, constructed substantially as herein shown and described, to adapt it for use in reducing the slots in a strainer-plate, as set forth.

JAMES ROBERTSON.
